UNITED STATES PATENT OFFICE.

WILLIAM F. STARCK, OF SAN FRANCISCO, CALIFORNIA.

SHOE RACK.

Application filed April 25, 1925. Serial No. 25,844.

To all whom it may concern:

Be it known that I, WILLIAM F. STARCK, a citizen of the United States, residing in the city and county of San Francisco and 5 State of California, have invented a new and useful Improvement in a Shoe Rack, of which the following is a specification.

My invention relates to improvements in shoe racks wherein a single wire or metallic 10 rod is bent to form upper and lower horizontal bars to engage and suspend one or more shoes vertically and adjacent a vertical surface to reduce the horizontal space required for storing, and wherein said rack 15 is also formed with legs having eyelets formed in the ends thereof whereby said rack may be secured in vertical position and in spaced relation to a vertical surface.

The primary object of the present invention is to provide a new and improved shoe rack.

Another object is to provide a new and improved device of the character described having improved and simplified means, permitting an economical production, for engaging and suspending one or more shoes in a vertical position and adjacent a vertical surface, such as the wall or on the inside of the door of a closet or other similar 30 compartment, in order to minimize the horizontal space occupied by said shoes.

A further object is to provide a shoe rack of the type set forth which may be easily and economically constructed from a single 35 piece or length of wire, so bent to form an entire and complete structure arranged to carry out the purposes of a shoe rack.

A still further object is to form a shoe rack from a single piece of wire or metallic 40 rod, and having upper and lower horizontal bars or rods to engage the heel and sole respectively of one or more shoes and effectively retain said shoes in a vertical position and adjacent a vertical surface such 45 as the wall of a small compartment or closet in order to reduce the horizontal or floor space occupied by said shoes when not in use.

I accomplish these and other objects by 50 means of the improved device disclosed in the drawings forming a part of the present specification wherein like characters of reference are used to designate similar parts throughout the said specification and drawings, and in which—

Fig. 1 is a perspective view of my im-

proved shoe rack, disclosing the manner in which the entire rack is formed from a single piece or length of wire; and

Fig. 2 is an end elevation disclosing the 60 shoe rack attached to a vertical surface and supporting a shoe.

Referring to the drawings the numeral 1 is used to designate an upper horizontal bar formed of a single piece or length of 65 wire or metallic rod having lateral portions on each end thereof formed into return bends to provide legs 2 having eyelets 3 arranged at right angles to the said legs 2 and slightly above the bar 1 when the 70 shoe rack is in a vertical or operative position, in order to hold the said bar 1 in spaced relation to a vertical surface 4, such as the wall of a closet or the inside of a door or small compartment, as disclosed in Fig. 75 2 of the drawings, the purpose of which spaced relation will hereinafter be more fully set forth.

After forming the legs 2 the wire is again bent substantially at right angles but downwardly and slightly inwardly toward the plane of the eyelets 3 to form vertical members 6 having formed at their lower ends suitable loops 7 whose inner sides are arranged to rest against the vertical surface 4, 80 and thence, continuing, the ends of the wire are bent at right angles to the legs or members 6 and toward each other where the said ends are firmly connected by twisting said ends together as at 8 in order to form a 85 lower horizontal bar 9 preferably arranged parallel with and directly below the upper horizontal bar 1.

While I have shown and described the 90 ends of the wire forming the shoe rack as being connected in the approximate center of the lower bar 9 it is obvious that said ends may effectively be connected in a number of other places within the shoe rack without departing from the spirit of the invention.

I prefer to connect said ends at said place as described, however, for the reason that when the rack is formed in such manner it provides a simple effective and expeditious 105 method of producing the shoe rack from a single length or piece of wire which will permit economy of production.

In operation the rack is placed against a vertical surface, such as the wall of a closet 110 or small compartment, or on the inside of a door and secured in such position by means

2 of screws 10 passing through the eyelets 3 and into said vertical surface 4, as disclosed in Fig. 2 of the drawings. The screws 10 hold the shoe rack firmly against said vertical surface with the upper rail or rod 1 in spaced relation to said vertical surface 4 so that the heel 11 of one or more shoes 12 may be hooked over or hung upon said rod 1 whereby said shoe 12 may be suspended 10 and supported in a vertical position and adjacent the vertical surface 4, this position being further supported by the lower rod or rail 9 which engages the sole at the toe of the shoe 12, thereby maintaining the said 15 shoe 11 in a vertical position where it will occupy less space horizontally than if the shoe or shoes were placed in their natural position upon the floor, thereby effecting a saving of space within closets and small 20 compartments, where space is at a premium, as well as saving the shoes from damage by being trod upon inadvertently.

Having thus described my invention what I claim as new and desire to secure by Letters Patent is—

1. A shoe rack for storing and holding shoes comprising a single wire bent to form upper and lower parallel and horizontally disposed bars and having legs formed with 30 eyelets therein adjacent the upper bar whereby said rack may be secured in spaced relation to a vertical surface, and loops formed adjacent the lower bar to engage said vertical surface and thereby hold said 35 lower bar in spaced relation to said surface, said upper and lower bars being arranged to engage the heel and sole respectively of one or more shoes and suspend the same vertically adjacent said vertical surface whereby said shoes may be stored with 40 in a minimum horizontal space.

2. A shoe rack for storing and holding shoes comprising a single wire bent to form a substantially rectangular frame having

upper and lower parallel and horizontal bars connected by substantially vertical end portions, said end portions and the upper horizontal bar having portions extended rearwardly in parallel proximate relation to form legs having eyelets formed at the ends thereof whereby said rack may be secured in spaced relation to a vertical surface; and rearwardly extended loops formed at the juncture of the lower bar and the end portions to engage the vertical surface and hold 50 said lower bar in spaced relation thereto, said upper and lower bars being arranged to engage the heel and sole respectively of one or more shoes and suspend the same vertically adjacent said vertical surface 55 whereby said shoes may be stored within a minimum horizontal space.

3. A shoe rack for storing and holding shoes comprising a single wire bent to form a substantially rectangular frame having 60 upper and lower parallel and horizontal bars connected by substantially vertical end portions, said end portions and the upper horizontal bar having portions extended rearwardly in parallel proximate relation to 65 form legs having upwardly turned eyelets formed at the ends thereof whereby said rack may be secured in spaced relation to a vertical surface; and rearwardly extended loops formed at the juncture of the lower 70 bar and the end portions to engage the vertical surface and hold said lower bar in spaced relation thereto, said upper and lower bars being arranged to engage the 75 heel and sole respectively of one or more 80 shoes and suspend the same vertically adjacent said vertical surface whereby said shoes may be stored within a minimum horizontal space.

In witness whereof I hereunto set my signature.

WILLIAM F. STARCK.
